UNITED STATES PATENT OFFICE.

BRODIE J. RICHARDSON AND CLAIRE S. BARBER, OF WATERBURY, CONNECTICUT.

LIFT-LATCH FOR HANDBAGS.

1,377,276.

Specification of Letters Patent. Patented May 10, 1921.

Application filed September 27, 1919. Serial No. 326,960.

To all whom it may concern:

Be it known that we, BRODIE J. RICHARDSON and CLAIRE S. BARBER, citizens of the United States, and residents, respectively, of Waterbury, in the county of New Haven and the State of Connecticut, have invented certain new and useful Improvements in Lift-Latches for Handbags, which improvements are fully set forth in the following specification.

This invention relates to improvements in devices of that class available for fastening purposes, particularly in conjunction with so-called hand-bags, valises, trunks, and analogous receptacles, such devices being well-designed lift-latches for handbags.

The object of this invention is to provide a lift-latch of the character above indicated which shall be simple and inexpensive as regards its construction; durable, efficient and reliable in practical service; convenient in its application to practical purposes; and which shall possess certain well-defined advantages over prior analogous devices.

The invention consists in certain combinations, details and parts whereby, together with the novel disposition and relative arrangement of said parts, the attainment of the foregoing object is rendered practicable, all of which will be hereinafter more specifically referred to and set forth in the claims hereto appended.

The invention is clearly illustrated in the accompanying drawing, wherein:

Figure 1 is a top plan view of a lift-latch embodying our said improvements, the latch-plate raised.

Fig. 2 is a side elevation thereof, the near side-wall of the base being removed.

Fig. 3 is a bottom plan view of same, the parts under adjustment as indicated in Fig. 1.

Fig. 4 is a view showing in perspective and detached the latch proper conjunctively with the pintle provided for co-operation therewith.

Fig. 5 is an end elevation of the device, the latch-plate raised.

Fig. 6 is a fragmentary face view showing the shouldered lower portion of the latch-plate.

Having reference to the accompanying drawing, wherein similar reference-numerals denote like parts throughout the several views, we provide a base-plate 2 surrounded

by a down-turned general wall, 2', consisting of opposite end-walls and opposite side-walls, as shown, and opposite fastening-tabs 2" 2''' being formed on the opposite end-walls, all as in common practice.

Base-plate 2 has a slot-like opening 3 formed longitudinally therein and a pin-exposing opening 3' formed transversely therein, somewhat rearwardly of the opening 3.

The material of the base-plate 2, at the opposite sides of the opening 3', is suitably drawn up to form opposite bearing-sockets 3" 3''', each open at the underside thereof and the function of which will be made clear hereinafter.

4 is a hinge-pintle which normally underlies the base-plate 2, in registry with the opening 3 and with its opposite ends projecting freely into the bearing-sockets 3" 3''', said hinge-pintle being reduced, preferably though not necessarily, at its opposite ends.

We provide and dispose at the underside of the base-plate 2 a resilient bolt-controller, preferably, though not necessarily formed from round steel wire and thereafter duly tempered, said controller being here shown as comprising opposite medial members 5' 5''' 6''', merged, respectively, into opposite, returned side-bars 5" 7', the medial members being integrally connected by an intermediate tie-segment 7.

The side-bars 5" 7' are upwardly crimped, 90 or similarly acted upon, to form therefor, respectively, upstanding or analogous bearing-segments 6" 7''', which detachably overlie, within the bearing-sockets aforesaid and when the parts are assembled, the hinge-pintle aforesaid at its opposite ends, and provide therefor, accordingly, downwardly-opening segmental bearings 6" 7''', operatively within which said hinge-pintle is yieldingly held through the medium of the 100 connected medial members 5' 5''' 6''', which jointly bear thereon midway therealong at the underside thereof.

4' denotes a finger-plate, reduced widthwise at its heel to form therefor opposite shoulders 8, 8' and a pintle-engaging extension 4'', said shoulders normally overlying the bearing-sockets 3" 3''', and said extension projecting downwardly through the base-plate 2, by way of the opening 3' 110 formed therein and fixedly engaging the hinge-pintle 4 thereunder, whereby said

finger-plate and said hinge-pintle may be rocked as a unit, the former upwardly from and downwardly upon the base-plate 2, and the latter within the segmental bearings 5 aforesaid provided therefor.

It may be here pointed out that the bolt controller aforesaid, hinge-pintle 4 and finger-plate 4', assembled as hereinbefore explained, are collectively interlocked and 10 held, severally and collectively, against casual displacement from the respective positions of service thereof, through the medium of the shoulders 8, 8', overlying and in coöperation with the bearing-sockets 3" 3", thereby avoiding the necessity for special fastening elements for any of said parts taken separately.

The finger-plate 4' carries the usual bolt 4", which operates upwardly and downwardly through the base-plate 2, by way of the opening 3 formed therein and in advance of the hinge-pintle 4, said bolt being fitted at its free end with the usual catch 5, whose function is to limit the upward throw of the 25 finger-plate 4' by engaging the base-plate 2 at the underside thereof and at the advance end of the opening 3, as will be readily understood.

That portion 6 of the extension 4", which 30 more immediately engages or encircles the hinge-pintle 4, is cut out, as at 5" to provide due clearance for the measurable occupancy of the free, connected end-portions of the medial members 5' 6", as clearly illustrated in Figs. 3 and 6 of the drawing, said medial members, particularly the free connected end-portions thereof, bearing, accordingly, jointly on the hinge-pintle 4, and normally exerting thereon, indirectly in this 35 instance through the medium of that portion 6 of the extension 4" engaging or encircling the same, a controlling yielding tension, which controlling tension, again through the medium of the finger-plate 4', is transmitted 40 to the bolt 4", whereby the latter is yielding controlled throughout all points of the rocking action of the finger-plate aforesaid which acts as a unit with the hinge-pintle aforesaid, as hereinbefore explained.

As will be quite readily understood, the controlling tension aforesaid may, when required, be measurably increased or intensified by duly deflecting away from the 55 hinge-pintle of our improved latch, the free edge-portion of the segment 6, as shown at 8", Fig. 2, increased deflection of the connected end-portions of the members 5' 6" being thereby effected upon the finger-plate 60 4' being duly rocked.

The base of the device may be drawn up from brass, bronze or other suitable material in sheet-form, or otherwise produced, as found desirable in practice, the fastening 65 tabs 2" 2"" being thus readily formed in-

tegral with the end-walls thereof; and the remaining parts of the device may be formed from any suitable material, round steel wire, as stated, being preferred for the bolt-controller aforesaid.

In applying our improved lift-latch for service, the fastening tabs 2" 2"" pierce, in the usual way, that hinged frame-section of the hand-bag or the like, on which the latch is to be mounted, said tabs being then 75 clenched or turned relatively to such frame-section at the underside thereof, all as common and well known in the art.

The operation of our improved lift-latch should be apparent from the foregoing description thereof; and it will be seen that the latch is well adapted for the purposes for which it is intended, comprising, as it does, parts which may be cheaply produced and readily assembled; and further that the 80 same may be modified to a considerable extent, particularly as regards the specific form of the resilient bolt-controller aforesaid, the specific form of the hinge-pintle made use of, and various minor details of the general construction, without materially departing from the spirit and principle of our invention as set forth in and coming within the scope of the claims hereto appended.

What is claimed is:

1. A lift-latch comprising a base-plate having a pintle-exposing opening formed therein, and having bearing-sockets rising therefrom; a hinge-pintle transversely underlying said base-plate; a resilient bolt-controller also underlying said base-plate, affording segmental bearings for said hinge-pintle and exerting thereon a yielding controlling tension; and a bolt-carrying finger-plate, the latter fitted with an extension operating within the pintle-exposing opening aforesaid, and firmly engaging the hinge-pintle thereat, for action as a unit therewith, and further provided with opposite shoulders overlying the bearing-sockets aforesaid, whereby the operative parts of the latch are interlocked against casual displacement.

2. A lift-latch comprising a base-plate having a pintle-exposing opening formed 115 therein and having bearing-sockets rising therefrom; a hinge-pintle transversely underlying said base-plate; a resilient bolt-controller also underlying said base-plate, said bolt-controller embodying opposite side-bars 120 overlying said hinge-pintle at its opposite ends and affording segmental bearings therefor, and further embodying connected medial members jointly underlying, and exerting a yielding controlling tension on, said 125 hinge-pintle; and a bolt-carrying finger-plate, the latter fitted with an extension operating within the pintle-exposing opening aforesaid and firmly engaging the hinge-pintle thereat, for action as a unit therewith, 130

and further provided with opposite shoulders overlying the bearing-sockets aforesaid, whereby the operative parts of the latch are interlocked against casual displacement.

3. A lift-latch comprising a base-plate having a pintle-exposing opening formed therein and having bearing-sockets rising therefrom; a hinge-pintle underlying said base-plate with its opposite end-portions projecting into said bearing-sockets; a resilient bolt-controller also underlying said base-plate, said bolt-controller embodying opposite side-bars upwardly crimped, respectively, for the formation therefor of

downwardly-opening segmental bearings, said segmental bearings occupying the bearing-sockets aforesaid, and wherein rockably bear the opposite end-portions of the hinge-pintle aforesaid, and further embodying connected medial members, jointly underlying, and exerting a yielding controlling tension on, said hinge-pintle; and a bolt-carrying finger-plate, the latter fitted with an extension operating within the pintle-exposing opening aforesaid and firmly engaging the hinge-pintle for action as a unit therewith.

BRODIE J. RICHARDSON.
